Specification for Design.

Patented Sept. 6, 1921.

Application filed February 18, 1921. Serial No. 446,179. Term of patent 7 years.

To all whom it may concern:

Be it known that I, FRANCIS H. WITTSTEIN, a citizen of the United States, residing at Newark, in the county of Essex and State of New Jersey, have invented a new, original, and ornamental Design for Finger-Rings, Bracelets, or the like, of which the following is a specification, reference being had to the accompanying drawing, forming part thereof.

Figure 1 is a side elevation of a finger ring showing my new design, and
Fig. 2 is an edge view thereof.

I claim:

The ornamental design for a finger ring, bracelet, or the like, as shown.

FRANCIS H. WITTSTEIN.
